UNITED STATES PATENT OFFICE.

WILLIAM ILE, OF JACKSON, MICHIGAN, ASSIGNOR TO REYNOLDS SPRING COMPANY, OF JACKSON, MICHIGAN, A CORPORATION OF DELAWARE.

DOUBLE LAMP SOCKET.

Application filed May 9, 1925. Serial No. 29,146.

The invention relates to a double lamp socket.

The object of the present invention is to improve the construction of double or two way lamp sockets of the ordinary type and to provide a simple practical and efficient double socket of strong, durable and comparatively inexpensive construction provided with a body portion consisting of a single 10 piece of molded phenol condensation product or other insulating material and having embedded therein the conductors for the screw shell contacts and the center contacts whereby the same will be firmly anchored and will 15 materially facilitate both the assembling of the parts of the double socket and the molding of the bakelite or other insulating material.

With these and other objects in view, the 20 invention consists in the construction and novel combination and arrangement of parts hereinafter fully described, illustrated in the accompanying drawings and pointed out in the claims hereto appended, it being understood 25 that various changes in the form, proportion and minor details of construction, within the scope of the claims, may be resorted to without departing from the spirit or sacrificing any of the advantages of the 30 invention.

In the drawings:

Figure 1 is a vertical longitudinal sectional view of the double lamp socket equipped with a detachable screw plug so as to provide a two in one socket to screw in an ordinary socket or receptacle or to present projecting terminals, blades or fingers for insertion in apertures of a fixture to engage 35 interiorly arranged contacts or terminals thereof.

Fig. 2 is an end view of one of the sockets the shell contact, center terminal and insulating disk being removed.

Fig. 3 is a similar view of the other socket.

Fig. 4 is a plan view of the double socket the screw plug being removed.

Fig. 5 is a detail view of one of the screw shell contacts.

In the accompanying drawing in which is 50 illustrated the preferred embodiment of the invention the double lamp socket comprises in its construction an insulating body 1 consisting of a single piece of molded insulating material and comprising a solid substantially cylindrical body portion 2 and

lower hollow cylindrical sockets 3 and 4 diverging downwardly and connected at their adjacent walls by an integral solid upwardly tapered connecting portion 5 forming a dividing wall as clearly illustrated in Fig. 1 60 of the drawing. The cylindrical solid top portion is exteriorly reduced to provide a shoulder 6 and to receive a lower base portion 7 of a screw plug 8 which is detachably secured to the cylindrical portion by the 65 means hereinafter described to enable the double socket to screw into an ordinary socket or receptacle and also to permit the double socket when the said plug is removed to be applied to a different character or fixture 70 having apertures for the reception of projecting fingers or blades of terminal conductor bars 9 and 10 which are embedded in the solid cylindrical portion of the body 1 at opposite sides of a centrally arranged 75 bushing 11 which is engaged by a screw or bolt 12 of the screw plug 8. The bushing 11 which is interiorly threaded is provided at the inner edge with a flange 13 forming a head and adapted to securely 80 anchor the bushing in the solid cylindrical portion of the body. The bushing is molded in the body and the flange may have either a smooth or corrugated periphery, corrugations being adapted to prevent any liability of the bushing working loose and 85 rotating when the screw or bolt is rotated. The screw or bolt 12 passes centrally through the screw plug and is provided at its outer end with a polygonal head adapted to be 90 engaged by a wrench or other tool for screwing the bolt into the bushing and for removing it therefrom. The double socket may be equipped with a screw plug or the latter may be omitted and when so equipped 95 the device constitutes a two in one socket or fixture.

The terminal conductor bar 9 is straight and its lower or inner portion is embedded in the body material and is securely anchored therein by means of a yoke 14 extending through the lower portion of the terminal conductor bar 9 to secure it to the same and having its terminals 15 bent at an angle and diverging downwardly and projecting at the top wall of the sockets 3 and 4 for the attachment of center contacts 16. The conductor rod constitutes a yoke for connecting the center contacts and it also serves 105 as means for electrically connecting the same 110

5 besides operating has a secure anchoring means for positively and firmly holding the straight terminal conductor bar 9 in the material of the socket body. The ends of
10 the center contact connecting yoke are headed as shown by a suitable tool and the center contacts consist of a strip of metal doubled to form upper and lower portions, the lower portion being provided with a cup-shaped
15 end 17 for contacting with a lamp. The lower or outer portion of the center contact 16 is adapted to be bent out of the way while the end of the connecting yoke is being headed and it may be readily bent back into position and arranged to insure its proper contact with a lamp.

The other terminal conductor bar 10 consists of a straight vertical upper portion, an intermediate inclined portion 18 and a straight inclined terminal contact portion 19 which is exposed at and arranged in flush relation with the interior of the socket 3 at the top wall thereof as clearly shown in Figs. 1 and 2 of the drawing. The angularly related upper portion, lower portion and intermediate portion of the terminal conductor bar 10 form and secure anchoring means for firmly holding the conductor bar in the molded material of the socket body. The upper or outer portions of the terminal conductor bars project above the cylindrical top portion of the socket body and form projecting contact fingers or blades adapted to enter the apertures 20 and 21 of the plug and provided with perforations 22 for engagement with protuberances 23 of interiorly arranged contacts or terminals 24 and 25 of the screw plug or similar electrical connections of an analogous fixture.

40 Each of the sockets 3 and 4 is provided at its top wall adjacent the dividing wall or portion 5 with an arcuate rib 26 projecting from the top wall of each of the said sockets 3 and 4 and adapted to fit in a curved slot 45 27 in the flange 28 of the screw shell contacts 29 and 30 of the sockets 3 and 4. The flanges of the shell contacts fit against the top walls of the sockets 3 and 4 and insulating disks 50 31 of grey fiber or other suitable material are interposed between the center contacts and the top walls of the sockets to insulate the center contacts from the shell contacts. The shell contacts and the disks 31 are placed in position prior to securing the center contacts to the terminals of the connecting conductor yoke 14. The inner terminal portion of the conductor bar 10 fits against the flange of the adjacent shell contact to establish an electrical connection between the two parts 55 60 and the dividing wall or portion 5 is provided with an aperture 32 and the adjacent portions of the shell contacts are also perforated at the said aperture to permit them to be soldered together as indicated at 33 in Fig. 1 of the drawing. This will electrically 65

connect the shell contacts with each other and current will pass through the shell contacts and the terminal conductor bar 10 as will be readily understood.

The outer ends of the sockets 3 and 4 are 70
inferiorly flared at 34 and are provided with
exterior circumferential beads 35.

It will be clear that the insulating body of the double socket may be molded of a single piece of bakelite and the conductor bars and connecting yoke and bushing embedded therein as inserts and that the parts may be rapidly and conveniently assembled and that the arcuate ribs which fit in the curved slots of the flanges of the shell contacts will interlock the shell contacts with the insulating body and prevent any relative rotary movement so that there will be no liability of the electrical connection between the shell contacts being effected by screwing lamps and removing them from the sockets as there will be no liability of such rotary movement of the lamps producing a rotary movement of the shell contacts.

The sockets are also provided at their top walls with studs or projections 36 which fit in perforations 37 of the flanges of the shell contacts and cooperate with the arcuate ribs in interlocking the shell contacts with the insulating body. 95

What is claimed is:

1. A double lamp socket including an insulating body consisting of a single piece of molded material and comprising a solid upper portion and downwardly diverging hollow cylindrical sockets and provided at the top walls of the said sockets with arcuate ribs and having studs spaced from the ribs, shell contacts arranged in the sockets and provided with flanges having apertures receiving the ribs and the studs whereby the shell contacts are interlocked against rotary movement, a straight vertical terminal conductor bar having its lower portion embedded in the solid portion of the body and provided with a horizontal yoke also embedded in the body at the solid portion thereof and having its terminals projecting at the top walls of the sockets, center contacts secured to the ends of the yoke, insulating disks interposed between the center contacts and the flanges of the shell contacts, a terminal conductor bar having a straight vertical upper portion, an angularly related intermediate portion and lower portion embedded in the solid top portion of the body, the angularly related lower portion being exposed at one of the said sockets and contacting with the flange of the contact shell thereof.

2. A double lamp socket including an insulating body consisting of molded material and including a solid upper portion and hollow cylindrical sockets and provided at the top walls of said sockets with arcuate 130

shaped ribs and having studs spaced from the ribs, shell contacts arranged in the sockets and having apertures receiving the ribs and the studs whereby the shell contacts
5 are locked against rotary movement, a terminal conductor bar having a portion embedded in the body and provided with a horizontal yoke also embedded in the body and having its terminals projecting at the top
10 walls of the sockets, center contacts secured

to the ends of the yoke, insulating disks interposed between the center contacts and the shell contacts, a terminal conductor bar having its inner end terminating at and exposed at one of the said sockets and contacting with the respective contact shell. 15

In testimony whereof I have hereunto set my hand.

WILLIAM ILE.
